Primary Examiner — George D. Kirschbaum*(74) Attorney, Agent, or Firm* — Andrew S. Langsam;
Law Office of Andrew S. Langsam, PLLCCLAIM

The ornamental design for a collapsible gold putting game, as shown and described.

DESCRIPTION

FIG. 1 is a front, top, left side perspective view of a collapsible gold putting game showing my new design; FIG. 2 is front elevational view of the golf putting game shown in FIG. 1; and,

FIG. 3 is a left side elevational view of the golf putting game shown in FIGS. 1 and 2, with the right side being a substantial mirror image thereof.

The broken lines representing a team logo form no part of the claimed design.
